NOZZLE AND SEAT STRUCTURE

Lucian Ring, Birmingham, Mich., assignor to Ring Aluminum Development Company, a corporation of Michigan

Application January 23, 1956, Serial No. 560,793

17 Claims. (Cl. 22—68)

This invention relates to die casting machines and refers more particularly to a nozzle and seat structure for die casting machines.

Die casting machines of the present type comprise a die cavity and a cylinder leading to the die cavity for introducing a charge of molten casting material thereto. Suitable means are provided for cooling the cylinder. The cylinder normally has an intake port and the discharge end of a supply tube or nozzle communicates with the intake port for delivering molten casting material into the cylinder.

It is desirable that the annular discharge end of the nozzle or supply tube engages the annular seat surrounding the intake port continuously throughout the full 360° thereof to prevent the escape of casting material and, where the casting material is drawn into the cylinder by vacuum, to provide a seal. However, because of the engagement of the supply tube with the intake port of the cylinder there is the danger that excessive heat will be withdrawn from the supply tube and as a result the molten casting material may tend to solidify in the supply tube and plug it.

With the foregoing in view, it is an object of this invention to provide a nozzle and seat structure which will permit of a tight sealing engagement, yet which will not result in excessive heat transfer from the supply tube to the cylinder.

Another object of the invention is to provide a nozzle and seat structure which will also reduce to a minimum or substantially eliminate wear between the engaging surfaces of the nozzle and seat.

Other objects of the invention will become apparent as the following description proceeds, especially when considered in connection with the accompanying drawings, wherein

Figure 1 is a semi-diagrammatic side elevational view of apparatus embodying the invention.

Figure 2 is a transverse sectional view of the apparatus, taken along the line 2—2 on Figure 1.

Figure 3 is an enlarged view, partly in section, of a portion of the apparatus.

Figure 4 is an enlarged fragmentary detail of a portion of Figure 3.

Figure 5 is a fragmentary detail view.

Referring now more particularly to the drawing, the machine comprises a stationary support or platen 10 having a stationary die part 12 secured thereto. A movable die part 14 is provided which is movable toward and away from the stationary die part. Movable die part 14 is carried by a carrier 15, slideable on rods 16, secured to platen 10. The carrier is reciprocated by the cylinder assembly 18, being secured to one end of the connecting rod 20, the other end of the connecting rod being connected to the piston (not shown) within cylinder 18.

The adjacent surfaces of the die parts engage each other in the closed position of the die and are formed with registering recesses to define the cavities 22. Molten

2

casting material which may be, for example, of the light-weight nonferrous type, such as aluminum, magnesium or zinc, is introduced into the die cavities by an injection cylinder or cold chamber 24. The cold chamber 24 is secured to platen 10 and projects through it and through the fixed die part 12 having its outer end communicating with the die cavities.

The cold chamber is in the form of an elongated tube which is formed with a plurality of elongated passages 26 having tubes 28 extending into the passages which are connected to coolant pipes 30. The passages 26 extend from the inner end 32 of the cold chamber to a point adjacent the outer end and the tubes terminate short of the outer ends of the passages and are of substantially less diameter than the passages to provide a return for the cooling medium introduced into the tubes 28 by the pipes 30. The coolant is withdrawn from the return by discharge pipes 34. By this means, the cold chamber 26 is maintained at a uniform relatively cool temperature.

A plunger 36 is supported for sliding movement within the tubular cold chamber 24. A rod 38 has one end connected to the plunger 36 and the other end may be attached to any suitable mechanism (not shown) for reciprocating the plunger 36 within the cold chamber.

The cold chamber has an intake opening or port 40 through its bottom wall which is spaced inwardly from the discharge or outer end 42. A frusto-conical seat 43 extends downwardly from port 40. The seat forms an angle of 45° to the axis of the cone which extends at right angles to the axis of the cold chamber. Seat 43, and in fact the entire cold chamber 24, is formed of air-hardened steel. Molten casting material forced into the die cavities by plunger 36 is initially introduced into the cold chamber through the intake opening. The plunger 36 is reciprocable between an inner position illustrated in Figures 1 and 3 at the inner side of the intake opening and an outer position located outwardly beyond the intake opening.

As seen in Figure 1, a container or reservoir 44 is located beneath the intake opening and is adapted to contain a supply of molten casting material 46. The container may be heated by any suitable means to maintain the casting material in a molten condition.

A vertical supply tube or nozzle 48 is provided for delivering molten casting material from the reservoir into the intake opening 40 of the cold chamber. The supply tube is formed of tungsten carbide with a cobalt binder. Alternatively the supply tube may be formed of a ceramic material, the principal constituent of which is carborundum (silicon carbide), with a suitable binder such as silicon nitride. The supply tube includes a tubular cylindrical portion 50, the lower end portion of which extends beneath the top surface of casting material in the reservoir. The cylindrical portion of the supply tube has a portion 52 adjacent the upper end thereof reduced in diameter for attachment to a supporting member 54. As shown in Figure 5, the opposite sides 56 of the reduced portion 52 are flattened to enable insertion of the reduced portion into a narrow slot 58 formed in the supporting member 54 and opening through one edge thereof. The slot 58 terminates in an enlarged portion which enables rotating the tube 48 to lock the same in assembled relationship with the supporting member 54.

The supporting member 54 is connected by vertical rods 60 to a cross bar 62 positioned above the cold chamber 24. The upper ends of the vertical rods are reduced to extend through openings formed in the cross bar 62. The upper extremities of the reduced portions of rods 60 are threaded and abutments 64 are secured to the upper extremities of the rods. Coil springs 66 are mounted on the reduced portions of the rods between the abutments 64.

and the cross bar. The cross bar 62 is slidable on the reduced portions and the purpose of the springs is to cushion engagement of the supply tube with the seat surrounding the intake port to the cold chamber upon upward movement of the cross bar.

The cross bar 62 is connected to a hydraulic motor 68 comprising a vertically extending cylinder 70 having a piston (not shown) connected by a rod 72 to the cross bar. Cylinder 70 is mounted on bracket 73 carried by support 10. Thus, vertical movement of the piston in cylinder 70 imparts a corresponding movement to the cross bar to move the supply tube vertically along its axis.

A bearing block 74 is formed with a vertically elongated longitudinally extending opening 76 for receiving the cold chamber 24. The lower end of the opening is shaped to provide an extended bearing contact with the adjacent outer surfaces of the cold chamber and the latter surfaces are maintained in contact with the block by set screws 78 threadedly supported in the block in positions to extend into the opening 76 and engage the cold chamber 24. The bottom of the block 74 is slotted to provide a clearance opening 89 directly opposite the intake port 40 to the cold chamber. The vertical rods 60 are respectively slidably received in vertical grooves 82 formed in the bearing block at opposite sides thereof.

The supply tube is of one-piece construction and has an integral nozzle portion 84 at the upper end. The upper end of the nozzle portion terminates in a flat annular surface 86 which extends at right angles to the longitudinal axis of the supply tube. The laterally outer surface 88 of the nozzle portion 84 is frusto-conical, its axis coinciding with the supply tube axis, and forms an angle of 15° with the longitudinal axis of the supply tube. The laterally outer surface 88 and the end surface 86 are connected by an annular surface 90 which is of convex arcuate cross section in planes through and including the longitudinal axis of the supply tube. The radius of curvature of the annular surface should be between one sixty-fourth of an inch ($\frac{1}{64}$ ") and three-sixteenths of an inch ($\frac{3}{16}$ "). In the present instance, such radius is one-eighth of an inch ($\frac{1}{8}$ "). The axis of the supply tube and of the surface 88 coincides with that of the seat 43.

The convex annular surface 90 is adapted to sealingly engage with the conical seat 43 continuously throughout the full 360° thereof when the supply tube is raised to the position shown in Figure 2. It is highly desirable for such a sealing engagement to result in order to prevent casting material from leaking at the intake opening and also to maintain a vacuum within the cold chamber where the charge of molten casting material is introduced thereto by vacuum.

The supply tube is held against the seat 43 of the cold chamber under a substantial pressure and therefore the annular surface 90 is rounded or convex for engagement with the frusto-conical seat. However, the radius of curvature should not be greater than $\frac{3}{16}$ of an inch in order to prevent the excessive transfer of heat from the supply tube to the relatively cool cold chamber. If a larger radius is employed, too great an area of surface-to-surface contact will result and the supply tube will be cooled excessively. If the supply tube is cooled excessively there is a tendency for the molten casting material to solidify therewithin and plug it.

If the radius of curvature of the surface 90 is too small, it will tend to coin or wear away the conical seat. Either of the materials specified for the supply tube is harder than the steel seat so that the supply tube nozzle will not wear. To prevent wear of the seat, it has been found that the radius of curvature of surface 90 should not be less than $\frac{1}{64}$ of an inch. If the seat 43 is coined by the nozzle portion of the supply tube, then the area of surface-to-surface contact would increase and likely cool the supply tube excessively. Then, too, if the seat 43 is coined, the seal between the nozzle and seat would no doubt be broken or at least reduced in effectiveness. The ideal radius of

curvature, all of the above factors considered, is $\frac{1}{8}$ of an inch.

The manner in which the molten casting material is moved through the supply tube into the cold chamber 5 may vary and forms no part of this invention and hence is not shown. Thus, when the piston is retracted to the Figure 3 position, the casting material may be forcibly pumped through the supply tube. On the other hand, 10 vacuum producing equipment may be connected with the cold chamber to, in effect, suck the casting material into the cold chamber when the piston is retracted to the position illustrated. The piston is thereafter moved outwardly beyond the intake port to force the casting material into the die cavities.

15 What I claim as my invention is:

1. In die casting apparatus including a die cavity and means providing a passage leading to said die cavity for introducing a charge of molten casting material thereinto, an intake port to said passage, a supply tube for delivering molten casting material to said passage through said 20 intake port, an annular seating surface surrounding said intake port, said supply tube including a nozzle portion at the discharge end thereof having an annular surface sealingly engageable with said seating surface continu-

25 ously throughout the full 360° thereof, one of said surfaces being frusto-conical and the other being of convex arcuate cross-section in planes through and including the axis thereof, the radius of curvature of said convex surface being within the range of $\frac{1}{64}$ of an inch to $\frac{3}{16}$ of an inch.

30 2. In die casting apparatus including a die cavity and means providing a passage leading to said die cavity for introducing a charge of molten casting material thereinto, an intake port to said passage, a supply tube for delivering molten casting material to said passage through said 35 intake port, a frusto-conical seat surrounding said intake port, said supply tube including a nozzle portion at the discharge end thereof having an annular surface sealingly engageable with said frusto-conical seat continuously throughout the full 360° thereof, said annular surface being of convex arcuate cross-section in planes through and including the axis thereof, the radius of curvature of said annular surface being within the range of $\frac{1}{64}$ of an inch to $\frac{3}{16}$ of an inch, said supply tube being movable toward and away from said intake port to relatively move said surface into and out of sealing engagement with said seat.

35 3. The apparatus defined in claim 2 in which said nozzle portion is formed of a material including tungsten carbide and said seat is formed of steel.

40 4. The apparatus defined in claim 2 in which said nozzle is formed of a ceramic material including silicon carbide, and said seat is formed of steel.

45 5. The apparatus defined in claim 2 in which the radius of curvature of said annular surface is $\frac{1}{8}$ of an inch.

50 6. In die casting apparatus including a die cavity and means providing a passage leading to said die cavity for introducing a charge of molten casting material thereinto, an intake port to said passage, a supply tube for delivering molten casting material to said passage through said intake port, a frusto-conical seat surrounding said intake port, said supply tube including a nozzle portion at the discharge end thereof having an annular surface sealingly engageable with said frusto-conical seat continuously throughout the full 360° thereof, said annular surface being of convex arcuate cross-section in planes through and including the axis thereof, the radius of curvature of said annular surface being within the range of $\frac{1}{64}$ of an inch to $\frac{3}{16}$ of an inch, said supply tube being movable toward and away from said intake port to relatively move said surface into and out of sealing engagement with said seat, said supply tube being formed of tungsten carbide with a cobalt binder and said seat being formed of air-hardened steel.

55 7. The apparatus defined in claim 6 in which the

radius of curvature of said annular surface is $\frac{1}{8}$ of an inch.

8. In die casting apparatus including a die cavity and means providing a passage leading to said die cavity for introducing a charge of molten casting material thereinto, an intake port to said passage, a supply tube for delivering molten casting material to said passage through said intake port, a frusto-conical seat surrounding said intake port, said supply tube including a nozzle portion at the discharge end thereof having an annular surface sealingly engageable with said frusto-conical seat continuously throughout the full 360° thereof, said annular surface being of convex arcuate cross-section in planes through and including the axis thereof, the radius of curvature of said annular surface being within the range of $\frac{1}{64}$ of an inch to $\frac{3}{16}$ of an inch, said supply tube being movable toward and away from said intake port to relatively move said surface into and out of sealing engagement with said seat, said supply tube being formed of a ceramic material including silicon carbide, and said seat being formed of air-hardened steel.

9. The apparatus defined in claim 8 in which the radius of curvature of said annular surface is $\frac{1}{8}$ of an inch.

10. The apparatus defined in claim 9 in which said frusto-conical seat tapers at an angle of 45° to its axis.

11. The apparatus as defined in claim 7 in which said frusto-conical seat tapers at an angle of 45° to its axis.

12. In die casting apparatus including a die cavity and means providing a passage for molten casting material to be introduced into said die cavity, an intake port to said passage, a supply tube for delivering molten casting material to said passage through said intake port, an annular seating surface surrounding said intake port, said supply tube including a nozzle portion at the discharge end thereof having an annular surface sealingly engageable with said seating surface continuously throughout the full 360° thereof, one of said surfaces being of convex arcuate cross-section in planes through and including the axis thereof, the radius of curvature of said convex surface being within the range of $\frac{1}{64}$ of an inch to $\frac{3}{16}$ of an inch.

13. The apparatus defined in claim 12 in which one of said surfaces is harder than the other.

14. The apparatus defined in claim 12 in which the convex annular surface is harder than the other surface.

15. In die casting apparatus including a die cavity

45

and means providing a passage leading to said die cavity for introducing a charge of molten casting material thereinto, an intake port to said passage, a supply tube for delivering molten casting material to said passage through said intake port, an annular seat surrounding said intake port, said supply tube including a nozzle portion at the discharge end thereof having an annular surface sealingly engageable with said seat continuously throughout the full 360° thereof, said annular surface being of convex arcuate cross-section in planes through and including the axis thereof, the radius of curvature of said annular surface being within the range of $\frac{1}{64}$ of an inch to $\frac{3}{16}$ of an inch.

16. The apparatus defined in claim 15 in which said annular surface is harder than said annular seat.

17. In die casting apparatus including a die cavity and means providing a passage leading to said die cavity for introducing a charge of molten casting material thereinto, an intake port to said passage, a supply tube for delivering molten casting material to said passage through said intake port, a frusto-conical seat surrounding said intake port, said supply tube including a nozzle portion at the discharge end thereof having an annular surface sealingly engageable with said frusto-conical seat continuously throughout the full 360° thereof, said annular surface being of convex arcuate cross-section in planes through and including the axis thereof, the radius of curvature of said annular surface being within the range of $\frac{1}{64}$ of an inch to $\frac{3}{16}$ of an inch, said annular surface being harder than said seat.
